UNITED STATES PATENT OFFICE.

WILLIAM B. MUNN, OF MEMPHIS, TENNESSEE, ASSIGNOR OF ONE-HALF TO ISADORE B. SCHARFF, OF MEMPHIS, TENNESSEE.

WRAPPING-MACHINE.

1,277,743.

Specification of Letters Patent.

Patented Sept. 3, 1918.

Application filed October 9, 1917. Serial No. 195,595.

To all whom it may concern:

Be it known that I, WILLIAM B. MUNN, a citizen of the United States of America, residing at Memphis, in the county of Shelby 5 and State of Tennessee, have invented certain new and useful Improvements in Wrapping-Machines, of which the following is a specification.

The present invention relates to improvements 10 in wrapping machines, and is designed particularly for the purpose of facilitating the wrapping of collars, cuffs, etc., in laundries.

The primary object of the invention is the 15 provision of a manually operated machine embodying means for forming a receptacle, preferably of paper, in which the collars or cuffs are deposited and providing a support for the laundry articles while the package 20 is being formed about one end of the support, and then transferring the partly formed package to another support where the other end of the package is formed and the package completed. The wrapper is 25 formed by cutting the required sheet from a roll of paper, after the preliminary paper receptacle has been formed about the support or core first mentioned. The invention 30 consists in the above set forth instrumentalities, and in certain other novel features and combinations and arrangements of parts as will be hereinafter more fully described and claimed.

In the accompanying drawings I have 35 illustrated one complete example of the physical embodiment of my invention constructed according to the best mode I have so far devised for the practical application of the principles of my invention.

40 Figure 1 is a top plan view of the machine embodying my invention.

Fig. 2 is an elevation view at the right hand side of Fig. 1, showing the formation of the package, collars being shown in the 45 packages in dotted lines.

Fig. 3 is a side elevation of the complete machine.

Fig. 4 is a front elevation of the machine.

Fig. 5 is a sectional view of a modification of the device.

In the preferred embodiment of my invention as illustrated in the drawings I utilize a table 1 having the usual legs or posts 2, 2, and upon the top of the table a roll of paper 55 3 is supported on the pedestal 4, and from

the spindle 5 the web 6 of the paper may be unwound as usual, the roll revolving, of course on the spindle.

A sheet of paper of the required size is severed from the roll by a paper cutting 60 wheel 7, carried by the cutter member 8, which has a handle 9, and the handle is passed through an opening in the table, in which it is guided, so that as the cutter is raised the cutting wheel travels over the 65 paper and severs it in usual manner. The wheel travels from the bottom edge of the web 6 to the top edge, and the web is supported against the back plate 10 which is 70 fixed to the table top and rises therefrom in the form of a vertically arranged bracket. A friction guide spring plate 11 is spaced 75 from the plate 10 on a pair of pins 12 12 and springs 13 on the pins clamp the web of paper between these two plates, the friction 80 however not being great enough to prevent pulling the paper web or sheet through the two plates. Thus the wrapper or wrapping sheet may be cut from the roll, and the web or free end of the roll is retained between 85 the spring plate and the back plate of the supporting bracket.

The sheet of paper that has been severed from the roll is to be wrapped about a core into a package, or rather, the sheet is 85 wrapped about the core 14 before it is severed from the roll, preparatory to depositing the collars or cuffs into the receptacle thus formed about the core. As illustrated, the core is a metal cylinder formed with an 90 annular flange 15 at its base which is a guide for the paper sheet, and directly below its closed bottom end, (closed except for a central perforation 16) the cylinder is fashioned with a flanged wheel portion 17 to accommodate an endless belt 19, by means of which, when the belt is driven, the core is 95 revolved, the lowermost flange 20 of the core being retained under the oppositely arranged clips 21, 21 secured to the table top. 100 The core rests upon the table top, or upon a bearing plate thereon, and is wound or revolved about its center, by the belt, to wrap the end of the paper roll thereabout as indicated in Fig. 3.

105 The core is provided with a movable bottom 22 in the form of an inverted, metallic cylinder, fitting neatly within the core cylinder 14, and forming a packing-plunger therein with which the collars and cuffs are 110

packed in their wrapper. A stem or plunger rod 23 depends from the plunger and passes through the opening 16 in the core and through a supporting opening in the table top, and thence through a lower supporting and guide block 24 fixed at the bottom of the table legs as shown. The plunger rod is thus supported in its bearings so that it may be reciprocated vertically, a lift cord 25 being attached to the rod for this purpose, and the cord passes over an idle pulley 26 just under the table top and then down to the foot treadle 27 pivoted at 28 in the table support. In Fig. 3 the parts are broken away to illustrate the use of this portion of the machine, and it will be observed that the paper is wrapped about the core and two collars have been deposited within the cylindrical core. After the paper has been severed from the roll, and previously wrapped around the core, the collars are deposited in the core, and then the top edge of the paper sheet projecting above the core, is folded over the top of the core to position indicated in Fig. 2, and the plunger is then raised to "pack" the collars, and finally to lift the entire package from the core, this action being assisted by the operator who grasps the package by hand, above the top of the lifted plunger in Fig. 2. The wrapping of the package or bundle is then completed by hand, and is accomplished by folding down the free end of the wrapper.

A modified form of the invention is also illustrated wherein the core 30 is movable instead of the plunger 31, which is fixed, the core being lifted by means of the treadle 32, cord 33, pulley 34 and stem 35. The collars are packed in the receptacle, and the receptacle folded and wrapped into a package in practically the same manner as in the first instance.

While I have described my invention as applied particularly to the wrapping of collars and cuffs, it will readily be understood that other articles may be wrapped and packaged with equal facility, so that I do not limit myself to the precise use described herein. The mode of operation and preferred construction illustrated in the draw-

ings has proven highly satisfactory in actual practice, but it will be apparent that changes and alterations may be made in the construction and arrangements of the machine as illustrated without departing from the scope 55 of my invention as contained in the following claims. As for instance, round pasteboard cards or disks C and C' may be utilized as in Fig. 2 to strengthen and brace the top and bottom of the package, and these 60 disks are inserted in the package during its formation, as will readily be understood.

What I claim is:

1. The combination in a package wrapping machine with a web feed roll, of a revoluble receptacle having an open upper end and adapted to wind said web upon itself to form a wrapper, a depressible support within the receptacle, and means for elevating the support to pack the contents 70 of the wrapper.

2. The combination in a wrapping machine with a supporting table and a web feed roll, of a cylinder revolvably supported on the table and adapted to wind said web 75 upon itself to form a wrapper, means for severing said wrapper from the roll, a depressible plunger within the cylinder, and means for elevating the plunger.

3. The combination in a wrapping machine with a table and web feed roll, of a receptacle revolvably supported on the table to wind the web thereabout to form a wrapper, a web supporting back plate on the table, means in operative relationship with 85 said plate for severing the wrapper from the roll, and a spring pressed guide plate for retaining the severed end of the roll.

4. The combination in a wrapping machine with a web feed roll, of a revolvably 90 supported, open ended, cylindrical receptacle having a lower, integral wheel portion and a base with a guide flange thereon, a depressible plunger within the receptacle having a stem projecting through the base of 95 the receptacle, and a treadle device for lifting the plunger and stem.

In testimony whereof he affixes his signature.

WILLIAM B. MUNN.
